UNITED STATES PATENT OFFICE.

WILLIAM A. HANNA, OF DEL NORTE, COLORADO.

CULINARY BEATER.

1,001,949.

Specification of Letters Patent. Patented Aug. 29, 1911.

Application filed January 13, 1910. Serial No. 537,885.

To all whom it may concern:

Be it known that I, WILLIAM A. HANNA, a citizen of the United States, residing at Del Norte, in the county of Rio Grande, 5 State of Colorado, have invented certain new and useful Improvements in Culinary Beaters; and I do hereby declare the following to be a full, clear, and exact description of the invention, such as will enable 10 others skilled in the art to which it appertains to make and use the same.

This invention relates to culinary beaters; and has for its object to provide a simple, cheap and efficient device for beating or 15 whipping cream to a foam, eggs and other substances in a rapid and thorough manner, and to this end, it comprises a suitable receptacle containing stirrers or beaters operated by gearing mounted on a frame re- 20 movably attached to said receptacle for the purpose of separating the parts to be cleaned.

With this object in view, the invention consists of the construction, combination 25 and arrangement of parts hereinafter described and claimed, and illustrated in the accompanying drawings, in which,

Figure 1 is a vertical sectional view of the beater; Fig. 2, a side elevation of the 30 same, looking in the direction of the arrow A, Fig. 1, showing the frame separated from the receptacle, and Fig. 3, a cross sectional view on the line 3—3 of Fig. 1. Fig. 4 is a top plan view.

Similar reference characters are used for 35 the same parts in all the figures.

In the drawings, 1 indicates a receptacle in which cream, eggs or other substances to be operated upon are placed. This receptacle may be made of sheet metal, glass, porcelain or other suitable material, but as 40 shown in the drawings, it consists of a cylindrical metal vessel provided with a closure 2 at the top and an exterior pocket 3 on each 45 side of the receptacle diametrically disposed and opening upwardly into which pockets, the lower tapered ends 4 of an inverted U-shaped frame 5 are placed. The pockets 3 are preferably tapered at the same angle as 50 the lower ends of the frame 5, so that the latter, when inserted therein may be forced downwardly and be held rigidly by frictional contact between the ends 4 and the interior of the pockets.

55 Mounted to turn in the upper end of the frame 5 is a horizontal shaft 6 having a

crank 7 midway its length and a small gear wheel 8 fastened on one end outside the frame 5. Projecting from the same side of the frame is a short stud 9, on which is 60 rotatably mounted a large gear wheel 10, held thereon by a pin 11, said gear wheel 10 meshing with the smaller gear wheel 8, to rotate the shaft when the larger wheel 10 is turned by a handle 12 projecting there- 65 from.

Pivottally connected to the crank 7 is a connecting rod 13 jointed at its lower end to a vertical rod 14 which extends through the closure 2 into the receptacle 1 nearly to the 70 bottom thereof. A beater or stirrer 15 is journaled on the lower end of the vertical rod 14, while a short distance above, is a flat perforated plate 16 fixed on said rod 14, and reaching nearly to the walls of the receptacle 75 1. The agitator or stirrer 15 comprises a hub 17 through which the rod 14 passes and a plurality of wings or blades 18, projecting radially in a horizontal direction and inclined on their own axes. Each blade is per- 80 forated, as shown, for more readily accom- plishing the object sought.

If it be desired to whip a quantity of cream to a foam, it is poured into the receptacle after removing the closure 2 for 85 that purpose and the gear wheel 10 turned by means of the crank 12. Motion is communicated through the parts shown to the rod 14, which is moved rapidly in a vertical direction carrying with it the agitator 15, 90 and the perforated plate 16, which stir the cream and thoroughly aerate it, thereby caus- ing the particles of cream to break up and imprison the air forced through them, which assumes the well-known globular form of 95 all foaming substances. The reciprocating movement imparted by the rod 14 to the agitator 15 causes the latter to rotate on said rod, because of the angular position of the blades 18; the combined rotary and recipro- 100 catory movements therefore increase the rapidity with which the cream is brought to the condition desired. The perforations in the plate 16, and the blades of the agitator enable these parts to pass through the cream 105 more rapidly and with better effect for foaming it than if they were solid, causing less resistance, and therefore easier operation. After using the device, the frame 5 may be withdrawn from the pockets 4, and the 110 parts thoroughly cleaned. If desired, the pin 19 uniting the vertical rod 14 and the

connecting rod 13 may be removed to enable the cleaning operation to be more quickly accomplished.

As clearly shown the circular perforated plate 16 is of a size to freely move in the receptacle 1 whereby the vertical reciprocating rod 14 is properly guided to hold the angularly and radially arranged blades 15 out of contact with said receptacle.

10 What is claimed is:—

A beater comprising a receptacle, a frame forming a part of the same, a crank-shaft journaled in said frame, means for rotating said shaft, a vertical reciprocating rod operated by said crank shaft, a plurality of

angularly and radially disposed blades secured to the lower end of the rod, and a perforated flat circular plate also secured to the rod above the blades and of a size to freely move in said receptacle whereby said rod is 20 properly guided in its movement and the blades held out of contact with the receptacle.

In testimony whereof, I affix my signature, in presence of two witnesses.

WILLIAM A. HANNA.
